HIS ATTORNEY.

UNITED STATES PATENT OFFICE

2,107,840

ORNAMENT

Albert T. Sebek, Chicago, Ill.

Application April 3, 1937, Serial No. 134,830

5 Claims. (Cl. 41—10)

This invention pertains to ornaments, and particularly an ornament designed as an accessory for automobile equipment.

Among its important objects the invention includes the provision of a body of ornamental outline having a recess adapted to fit upon an oval extension of an ornamental handle structure used on a well known make of car.

A further object is the provision of a device of the class described in which the recessed body portion has a pair of oppositely disposed extensions having registered openings through which an attaching member or pin is extended to hold the ornament on the mounting member or handle.

Still another object is the provision of a device of the class described in which the recessed part of the ornament body is dimensioned to fit freely but snugly upon the mounting member or handle, which construction, together with the pin means above mentioned, provides a substantial yet simple support for the ornament.

Still another object of the invention is the provision of a device of the class described in which the ornament body is designed with its several structural characteristics above mentioned and its overall contour adapted to supplement the design contour of the mounting body or handle with which it is associated.

Other novel aspects and objects of construction will appear as the following detailed description proceeds in view of the drawing, in which

Fig. 1 is a top plan view of the ornament mounted upon a standard handle;

Fig. 2 is a side elevation of the combined ornament and handle, and is taken in the direction of lines 2—2 of Fig. 1;

Fig. 3 is a foreshortened bottom plan view looking in the direction of lines 3—3 of Fig. 2;

Fig. 4 is a front elevation of the device of Fig. 3, and is taken along lines 4—4 thereof; while

Fig. 5 is an enlarged fragmentary vertical section through the handle and ornament, and taken along lines 5—5 of Fig. 4.

The device of the present invention includes an ornament body 10 having a central body portion 12 from which extend opposite winged portions 14 symbolizing in configuration, for example, the figure of a flying fish or the like.

The central body portion 12 includes, as seen particularly in Fig. 2, a pair of rearwardly extending arms 16, each provided with registering apertures 18 for the reception of a mounting pin or member 20. Disposed above the arms 16 and between the same is a rearwardly pointing vane

or body portion 22 which flows from the general oval contour of the central body portion and which may have its innermost surface 23 slightly dished or curved to fit closely against the complementary curvature of the underlying surface portion of a handle member 8.

Between the rearwardly extending vane 22 and the side arms 16, the body portion of the central body member 12 is cut away along a curved line, as indicated at 24, and similarly the bottom portion of the ornament between these arms 16 is cut away along an arcuate path, as indicated at 26, the purpose of these cut-away portions being particularly set forth hereinafter.

The mounting member 8, seen especially in Figs. 1, 2, and 5, is preferably an ornamental handle which at the present time is standard equipment on at least one well known make of automobile, and which is attached to the radiator peak portion of a hood and supplants the heretofore common radiator cap of ornamental design, and in addition to serving the utilitarian function of a handle for raising and lowering the hood, the member 8 additionally serves as an ornament.

As seen in the figures particularly referred to above, this member 8 is an elongated structure which tapers into a tail portion 9 of no particular consequence in the present case other than the fact that this formation blends into the overall artistic configuration of the handle structure itself and the combination of the handle and the ornament. In addition, the handle member 8 has a substantially solid oval nose portion or extension 11 (Fig. 5) from a lowermost portion of which depends a mounting stud or extension 13 threaded to receive a mounting bolt 15.

It will be understood that the handle 8 may be variously designed from an artistic standpoint, while including in each of these designs the peculiar oval extension or nose formation 11, and this latter fact is of importance in conjunction with the device of my invention, in that said device is peculiarly arranged and designed for supporting cooperation with an ornamental device of the character pointed out.

To this end the central body portion 12 is recessed or hollowed to provide a socket generally indicated at 17 in Fig. 5, and which receives the nose portion 11 of the handle 8, it being observed that the extreme outermost end 11' of the nose fits snugly against the bottommost (outer) part of the socket 17 and cooperably with the vane portion 22, and the arcuated bottom portion 26 provides a bearing engagement with

the handle member 8 so that when the stay pin 20 is inserted through the registered openings 18 and the handle member 8, a substantially rigid structure results.

- 5 5. The simplicity of the foregoing construction, and particularly the arrangement which includes the socket 17 receivable on the extended part of the handle 8 and the single stay pin 20, makes the device very useful as an accessory, since only 10 one hole need be provided or drilled in the handle portion in order to mount the ornament, yet the resulting ornament unit is extremely rugged and will resist ordinary attempts to remove the ornament part of the combination.
- 15 15. As has been pointed out previously in describing the particular handle structure 8 employed for illustrative purposes herein, the artistic design of the ornament 10 is not restricted to the particular form shown, for instance, in Fig. 1, but 20 may be varied through a wide range of ornamental designs such as will occur to those skilled in the arts, so that it is not intended that the invention be restricted to any of the particulars recited herein, but is to include all modifications 25 of the particularly described device and all adaptations of the same fairly coming within the scope of the appended claims, and which particularly may include an ornament body having a substantially oval socket therein for the reception 30 of a substantially oval body extension of a mounting member, and pin means adjoining the juncture of the ornament and the mounting member at a point spaced substantially away from the bottom of the recess.
- 35 35. Having thus described my invention, what I claim as new and desire to protect by Letters Patent is:

1. An ornament body having a recessed portion providing a socket for the reception of a substantially oval extension of a mounting member, a mounting member extended into said socket,

and pin means extended through said ornament body and said mounting member at a point spaced substantially away from the bottom of said recess.

2. An ornament including a member having a 5 hollow body portion providing a socket of substantially elongated oval longitudinal cross-section, a mounting member having an elongated oval extension fitted into said socket, and means attaching said hollow body portion to said mounting member in assembled relation at a point spaced substantially away from the bottom of said socket.

3. An ornamental device in the form of a handle member having a substantially bullet shaped 15 extension and an ornament body having a socket formation conforming substantially to the outline of said extension and fitted over the same, together with pin means extended through said ornament and said handle member at a point 20 adjacent the juncture of said handle and the edge or rim portions of said socket.

4. An ornament body having a recessed part providing a socket of greater depth than width and fitted closely upon an oval receiving body, 25 said ornament being attached to a said body by pin means extended through the latter and said ornament at a point closer to the marginal rim extremity of said socket than to the bottom of the same.

5. An ornament having an elongated recess and fitted upon a mounting member having a part extended into said recess and against the bottom of the same, and means securing said ornament and said mounting member in assembled relation and including a securing member extended through said mounting member and said ornament at a point near the open end of said recess.

ALBERT T. SEBEK. 40
